COMBINED OBSERVATION PLATFORM AND STORAGE TANK

Ernest W. Boodt, Indianapolis, Ind., assignor to Universal
Tank & Iron Works, Inc., Indianapolis, Ind.

Filed Nov. 24, 1972, Ser. No. 309,052

Term of patent 14 years

Int. Cl. D23—01

U.S. Cl. D23—2

Fig.1

Fig.2

Fig. 3

Fig. 4

FIG. 1 is a front elevation of a combined observation platform and storage tank showing my new design.

FIG. 2 is a rear elevation thereof.

FIG. 3 is a top plan view thereof.

FIG. 4 is a side elevation thereof.

The opposite side of a combined observation platform and storage tank, from that illustrated in FIG. 4 is the mirror image of FIG. 4. The arches immediately beneath the ball in the upper portion of the tank and the arches immediately under the observation platform have vertical flat sides and are disposed at 120° relative to one another. The observation platform is circular in configuration.

I claim:

The ornamental design for a combined observation platform and storage tank, as shown and described,
